Specification for Design.

Patented Aug. 3, 1920.

Application filed May 26, 1920. Serial No. 384,476. Term of patent 7 years.

To all whom it may concern:

Be it known that I, JAMES D. TEW, a citizen of the United States, residing at Akron, in the county of Summit and State of Ohio, have invented a new original, and ornamental Design for a Pneumatic-Tire Tread, of which the following is a specification, reference being had to the accompanying drawings, forming a part thereof.

Figure 1 is a plan view showing a segment of a pneumatic tire bearing my new design. Fig. 2 is a cross section, omitting internal structural details of the tire wall.

I claim:

The ornamental design for a pneumatic tire tread as shown.

JAMES D. TEW.
